CAVITATION CONTROL MEANS FOR
BLADE PERIPHERY

Lewis Ferry Moody, Princeton, N. J., assignor to
Baldwin-Southwark Corporation, a corpora-
tion of Delaware

Application December 29, 1933, Serial No. 704,451

4 Claims. (Cl. 253—117)

This invention relates generally to improved means for reducing or eliminating cavitation at the periphery of unshrouded blades of rotary hydraulic machines, such as hydraulic turbines or pumps, although the invention is especially described in its application to turbines.

Cavitation has been one of the major problems with rotary hydraulic machines, and various arrangements and solutions have heretofore been proposed for controlling or eliminating cavitation at those parts of the equipment where cavitation is most likely to occur.

My present invention has particular reference to the cavitation at the periphery of unshrouded runner blades, and it is one object of my invention to provide improved means for reducing cavitation at this point. A further object is to provide a relatively simple arrangement which will not only function to reduce cavitation but also reduce leakage between the runner periphery and the surrounding stationary passage wall.

A more specific object of the invention is to provide improved means whereby a double pressure reduction occurs as water flows through the clearance space around the runner periphery, the peripheral portion of the blades being recessed to deliberately provide a region of eddy currents at a point where cavitation most likely occurs. Specifically this is accomplished by slotting the peripheral edge of the runner blades while maintaining the normal peripheral clearance at the face and back of the blades.

Other objects and advantages will be more apparent to those skilled in the art from the following description of the accompanying drawing in which:

Fig. 1 is a diagrammatic vertical sectional view of one form of propeller runner embodying my invention;

Fig. 2 is an enlarged fragmentary sectional view of a blade and a surrounding passage wall showing the manner in which internal eddy currents are formed at the periphery between the face and back surfaces of the blade;

Fig. 3 is a modified arrangement of peripheral grooves whereby three pressure reductions occur;

Fig. 4 is a further modification of the peripheral grooves whereby the length of each narrow clearance passage is reduced to zero by the use of triangular grooves.

In the particular embodiment of the invention which is disclosed herein merely for the purpose of illustrating one specific form of the invention among possible others that it might take, I have diagrammatically shown a conventional type of

rotary hydraulic machine specifically a turbine having a head cover 1, adjustable inlet guide vanes 2, a transition space 3 in which the water is turned from a radial toward an axial direction to flow through an unshrouded runner generally indicated at 4. This runner is disposed within a suitable passage 5 whose stationary wall 6 preferably, but not necessarily, of cylindrical form, has a close running clearance with the periphery 7 of each of the several runner blades 8. The runner may, of course, be of any usual form whether of the axial or diagonal flow type or it may have adjustable or non-adjustable blades. In any case, however, the peripheral edge of the blades is provided with a groove or slot generally indicated at 9. This groove may extend for the full peripheral length of each blade as diagrammatically indicated by line 9a or may as shown at 9b in Fig. 1 terminate slightly short of the leading and trailing edges 10 and 11 respectively. This peripheral groove may be of any sufficient depth to accomplish its purpose, but it is preferably of sufficient depth that the inner surface 13 is not within the range of the eddy currents indicated within the groove by arrows in Fig. 2. However, if the design of the runner blades is such that a groove of the foregoing depth cannot be conveniently used, then the groove may be made more shallow, while at the same time obtaining the general advantages of my improved arrangement. Preferably the ratio of the depth of groove to the width of clearance should be at least 2 to 1, or in another aspect, the groove should have a width at least equal to its depth.

As a consequence of my improved arrangement it is seen that a double clearance is provided, one at 14 and the other at 15, with the result that the hydraulic fluid will undergo one loss of head due to sudden enlargement in passing through clearance 14 into groove 9 and a second loss of head in passing from groove 9 through clearance 15 to the draft tube 5. At each point of enlargement velocity head is dissipated in eddies, thus reducing the effective head causing the leakage flow. Hence there is a material reduction in the velocity and leakage of the fluid through the peripheral clearance and this is accompanied by a lower velocity and higher pressure within groove 9 than would occur if the peripheral edge of the blade were straight or continuous with only a single pressure reduction. Also by my improved arrangement the surface 13 may if desired be positioned clear of the region of high velocity and intense eddy currents within groove 9, thus reducing or eliminating pitting of the peripheral

edge of the blade, although as previously pointed out this surface may be moved nearer to the blade periphery and due to the pressure built up within the groove caused by the double reduction at clearances 14 and 15, cavitation will be materially controlled without excessive detrimental effects.

In the modification shown in Fig. 3, I have multiplied the effect of the Fig. 2 form by providing a pair of grooves 16 and 17, thereby providing pressure reductions at clearances 18, 19 and 20. This modified arrangement is applicable where the runner blade thickness is sufficient to permit the use of two or even more grooves. Near the ends of the blade periphery where the blade is relatively thin, one of the grooves may terminate and a single groove continue.

In the modification of Fig. 4, the grooves are made triangular, cutting away all or nearly all of the parallel narrow clearance passage, and controlling the leakage flow entirely by a series of enlargements. Here the peripheral surface subject to cavitation has been eliminated, the flow being required to pass a series of relatively sharp corners where the velocity past the corner is made to enter an enlarged chamber in which a part of its kinetic energy is dissipated in eddies without harmful effects.

From the foregoing disclosure it is seen that I have provided an extremely simple and yet very effective means for reducing or eliminating cavitation at the blade periphery, this being accomplished without weakening the blade in any way and at the same time reducing the leakage through the clearance space. The reduction of the velocity of leakage flow through clearance 15 reduces the tendency toward cavitation on the under side of the blade near the peripheral edge due to the eddy produced by this leakage flow as it leaves the clearance space.

It will of course be understood that various changes in details of construction and arrangement of parts may be made by those skilled in the art without departing from the spirit of the invention as set forth in the appended claims.

45

I claim:

1. A hydraulic machine having a runner and inlet and outlet passages therefor wherein water pressures above and below atmosphere normally exist on opposite sides of the runner, said runner having a hub and a series of separate unshrouded propeller blades projecting from said hub at spaced points on a circle thereof, and each of said blades being provided with a normally peripheral groove formed as a recess between the front and back blade surfaces to control cavitation at the blade peripheries. 5

2. The combination set forth in claim 1 further characterized in that said blade peripheries are each provided with a plurality of grooves thereby 15 to effect multiple contractions and enlargements of the passage for leakage flow between the runner periphery and surrounding passage wall.

3. A hydraulic propeller type turbine having an unshrouded propeller runner disposed within a 20 passage which comprises an inlet and draft tube and has a wall immediately surrounding the runner periphery with clearance therebetween, the peripheral edge of said runner blades having a normally open groove therein providing a re- 25 cessed peripheral surface disposed entirely between the face and back surfaces of the blade, to control cavitation at the blade periphery, said recessed surface being set back from the region of high velocity leakage flow passing through said 30 clearance.

4. A rotary hydraulic machine having unshrouded blades, a stationary passage wall immediately surrounding said runner and having restricted clearance around said blades, the peripheral edges of said blades adjacent said wall being cut away by normally open grooves located entirely between the front and back blade surfaces and so formed as to form a succession of 40 ridges followed by enlarged spaces for controlling cavitation at the blade periphery, the surfaces of said blades and said stationary wall being angularly related. 35
